(57) **CLAIM**

We claim the ornamental design of an armrest, as shown and described.

DESCRIPTION

FIG. 1 is a front, top perspective view of an armrest showing an embodiment of our new design;

FIG. 2 is a top plan view of the armrest of FIG. 1;

FIG. 3 is a bottom plan view of the armrest of FIG. 1;

FIG. 4 is a left-side elevated view of the armrest of FIG. 1;

FIG. 5 is a right-side elevated view of the armrest of FIG. 1;

FIG. 6 is a front elevated view of the armrest of FIG. 1; and,

FIG. 7 is a rear elevated view of the armrest of FIG. 1.

The broken lines in the drawings illustrate portions of the armrest that form no part of the claimed design.
